OR D 11,539

No. 11,539

DEC 9, 1879

UNITED STATES PATENT OFFICE.

JAMES H. WHITE, OF MERIDEN, CONNECTICUT, ASSIGNOR TO THE WILCOX & WHITE ORGAN COMPANY, OF SAME PLACE.

DESIGN FOR AN ORGAN-CASE.

Specification forming part of Design No. **11,539**, dated December 9, 1879; application filed October 15, 1879.
[Term of patent 7 years.]

To all whom it may concern:

Be it known that I, JAMES H. WHITE, of Meriden, in the county of New Haven and State of Connecticut, have invented a new Design for Organ-Cases; and I do hereby declare the following, when taken in connection with the accompanying drawing and letters of reference marked thereon, to be a full, clear, and exact description of the same, which said drawing constitutes part of this specification, and represents perspective view.

This invention relates to a design for the case of musical instruments, with special reference to reed-organs; and it consists in the configuration and ornamentation, as shown in the accompanying illustration.

The ends of the case represent a raised panel, A, extending from the base upward; and near the top and bottom of the panel is a transverse band, *a a*, of lighter-colored material than the body of the panel, so as to show a strong contrast and clearly define the band, as shown in the accompanying illustration.

The key-section extends forward in the usual manner, and is represented as supported by a truss or bracket from below. This bracket has a scroll-shaped foot, *b*, projecting from the base, on the top of which rests a reverse scroll-shaped section, *c*. On top of the section

c stands a square post, *d*, and from the upper end of this post is an outwardly-curved scroll-shaped head, *e*, extending up to the key-section.

In the front, beneath the key-section and above the pedals, is a triangular panel, B, with the point upward, and a smaller triangular panel, D, at each side, the outer vertical bars of which form the sides of the central section in that part of the case.

I claim—

1. The design for an organ-case, consisting of the raised end panel, extending from the base upward, with transverse band *a* at top and bottom, as described, and shown in the accompanying illustration.

2. The design for an organ-case, consisting of the scroll-shaped foot *b*, scroll-section *c* above, square post *d*, and scroll-shaped head *e* beneath the key-section, as described, and shown in the accompanying illustration.

3. The design for an organ-case, consisting of the triangular panel B, above the pedals, and side triangular panels, D D, as described, and shown in the accompanying illustration.

J. H. WHITE.
